UNITED STATES PATENT OFFICE.

PIETRO V. MARTINO, OF NEW YORK, N. Y.

HAT-FORMER.

1,168,665.

Specification of Letters Patent.

Patented Jan. 18, 1916.

Application filed October 15, 1914. Serial No. 866,744.

To all whom it may concern:

Be it known that I, PIETRO V. MARTINO, a citizen of the United States, residing at New York, in the county and State of New York, have invented certain new and useful Improvements in Hat-Formers, of which the following, taken in connection with the accompanying sheet of drawings, is a full, clear, and concise description.

10 The present invention relates generally to improvements in hat forming devices and is more specifically directed to the production of hat blocks for forming that particular style of head gear or head-dress, in which 15 the crown is indented or telescoped.

In the production of headdress or hats having telescoped or indented crowns, it is now customary to employ a block on which the fabric is stretched preparatory to the 20 shaping operation and a former to which the fabric is then applied for shaping. It is obvious that this necessity for using two blocks is a decided disadvantage, particularly by reason of the fact that it increases 25 the cost of production of a hat and compels a manufacturer to carry a large supply of blocks, which naturally requires considerable space for storage. Furthermore, it is manifest that in employing two blocks in 30 the manner just referred to, the crown of the hat cannot be produced with the precision and symmetry, which is demanded by fastidious dressers, since after the fabric has been stretched on the stretching block 35 and then removed to the shaping block, it cannot be shaped or formed to the desired configuration as readily as would be the case were the entire operation carried out on one block. Many other disadvantages of the 40 employment of the present method of forming telescoped hat crowns exist, and are well known to those skilled in the art to which this invention appertains.

The present invention is designed to obviate the disadvantageous features of the existing types of hat formers or blocks, particularly those employed for the production 45 of hats having a telescoped crown, and one of its principal objects is to provide a means 50 for doing the work, which will consist of a single block, a portion of this block being adjustable so that the fabric may be prop-

erly and accurately positioned and stretched upon the block for the forming or shaping operation, after which these parts are again 55 relatively adjusted and the shaping operation performed without removing the fabric from the block. By the employment of my invention in this way, it will not be necessary to transfer the fabric from one block 60 to the other as is at present the case, all of the operations incident to the stretching of the fabric, being performed on a single block. Furthermore, by the employment of my invention, a device is provided which may be 65 simply and economically produced and which by the arrangement of its parts may be assembled with facility and produce a solid and durable device, which will greatly aid in reducing the expense of hat production 70 as compared to existing methods.

A further object of my invention is to provide a hat block or former, possessing the advantages above enumerated, which will reduce the waste of the fabric or material 75 from which the hats are produced to a minimum and will embody means in its construction, whereby the fabric from which the hat is made, may be applied and secured thereto in a manner which will enable the 80 user of the block or former to obtain a perfectly telescoped crown, the indentation surrounding the periphery or edge of the crown being of like dimensions throughout. This is impossible of accomplishment with the 85 present type of formers or blocks, owing to the lack of efficient means for measuring and applying, and securing the fabric in place prior to manipulation or shaping. Many other advantages incident to the employment of my invention will be observed 90 as the description proceeds.

To render a clear and comprehensive description of my invention, I have elected to illustrate and describe a specific embodiment 95 thereof, it being obvious that various details of structure may be changed without departing from the spirit and scope of my invention.

I shall now proceed to describe my invention with reference to the accompanying sheet of drawings, and then point out with more particularity, the essential elements of novelty therein in the appended claims.

In the drawings: Figure 1 is a sectional elevation showing the body of the block and the crown or head piece thereof, in adjusted position with the fabric stretched thereover prior to the forming operation, and Fig. 2 is a sectional elevation showing the crown or head piece seated upon the body portion of the block with the former in engagement with the fabric.

10 Referring now to the drawings in detail, in which like characters of reference are employed to indicate similar parts throughout the several views, 7 represents the body portion of the block, which may be made of wood or any other material, suitable for the purpose. As is well known, the blocks for forming head-dress are made of various dimensions and in many configurations to suit the different shapes of heads of wearers 15 of the products to be made thereon, and it is obvious that my improved hat block is adapted to these various requirements in a like manner. It will be observed that the body of the block 7 is provided with two vertically directed, preferably cylindrical bores 8, which form bearing surfaces or guide ways for the rods 9, which are 20 slideable therein, the upper ends of these rods 9^a being embedded and rigidly secured within the head or crown piece 10 which 25 is adapted to be seated upon and form a part of the body portion 7 of the block as hereinafter explained. Centrally positioned in the body portion of the block 7 is a recess 30 11, whereby the block may be mounted upon the usual jack or other suitable supporting standards (not shown) when in use. The base of the block or body portion 7 adjacent to the bores 8 is provided with the preferably metallic fittings 12, which are 35 rigidly secured thereto in any suitable manner, such as by means of screws 13, each of these fittings being apertured at 14 to receive a pin 15 having an angularly bent portion 16 at one extremity to provide a handle or gripping part for actuating the same 40 within said apertures.

45 In the employment of my invention, the head or crown piece 10 is raised to the position shown in Fig. 1 and supported in that manner by inserting the pin 15 within the lowermost laterally directed socket 17, in each of the rods 9. The fabric 18 is then applied as shown in Fig. 1 and firmly secured to the body portion 7 of the block 50 by means of a tie-band 19, which forces the fabric into engagement with the cut-out portion 20, surrounding the lower edge of the body portion 7 of the block. It will be 55 noted that when the head or crown piece 10 is in the position shown in Fig. 1, the space between the upper surface A of the body portion 7, and under surface B of the head or crown piece 10 is approximately 60 that of the height of the upwardly directed 65

flange 21, surrounding the top of the body portion 7 of the block, plus the distance from the inner wall of this flange to the outer edge C of the wall of the head or crown piece 10.

70 When the fabric 18 has been applied as just described, the crown or head piece 10 is then lowered to its seat on the top of the body portion 7, as shown in Fig. 2 by the withdrawal of the pins 15 from the lowermost sockets in the supporting or adjusting rods 9. The crown or head piece is then locked in position on the top of the body portion 7 by re-inserting the pins in the upper or second laterally directed socket 75 21^a in each of said rods, as is clearly apparent from Fig. 2. The former 22 having the centrally positioned aperture 23 for permitting application of heat to the fabric on the block is now brought into use, the 80 edge of the depending flange 24 engaging the fabric 18 and, under pressure, forcing it down into the space formed by the inner face of the upwardly directed flange 21, and the outer wall C of the head or crown piece 85 10, the relative position of these parts in the manner described with reference to Fig. 1, providing for the production of a perfect and symmetrical telescoping effect, as is manifest from the coöperative relation 90 of the parts as shown in Fig. 2.

95 When the former 22 has been forced into the position shown in Fig. 2, the fabric 18 is dried out in the usual manner by the application of heat through an aperture or orifice 23, so that when the fabric is removed from the body portion 7 of the block by the loosening of the tie-band 19, the contour of the fabric producing the telescoped effect will be substantially permanent.

100 If desired, it is apparent that the base of the block shown may be provided with an outwardly directed flange for forming the hat rim, this outwardly directed flange being made as an integral part of the block 105 or arranged to be adjustable or detachable.

110 Other modifications of my invention may be effected to permit its application to the production of various forms of head-dress, all of which are within the spirit and scope 115 of my invention, which is broadly directed to the provision of an adjustable hat block or former for the production of head-dress having a telescope or indented crown.

120 Having thus described my invention what I claim as new herein and desire to secure by Letters Patent is:

1. A two-piece hat block comprising a body portion and a vertically adjustable head portion adapted to coöperate therewith to form a telescopic hat crown.
- 125 2. A hat block comprising a body portion and a head portion vertically adjustable relatively thereto and adapted to coöperate therewith to form a fabric guide and means 130

arranged to coöperate with said body and head portions to produce a telescopic hat crown.

3. A hat block comprising a body portion and a head piece mounted thereon and vertically adjustable relatively thereto, means carried by said body portion to coöperate with said head piece to provide a die for a hat forming fabric and means normally independent of said block and arranged to coöperate therewith to produce a telescopic hat crown.

4. A hat block comprising a body portion, and a head piece mounted thereon, guide ways formed in said body portion, rods rigidly secured to said head piece and movable within said guide ways to adjust said head piece relatively to said body portion and means for engagement with said rods to lock said head piece against movement.

5. A hat block comprising a body portion having an upwardly directed flange surrounding the upper edge thereof, a plurality of guide-ways formed in said body portion, a head piece adapted for seating upon said body portion to lie within said flange, rods rigidly secured to said head piece and movable in one direction within said guide-ways to raise said head piece from engagement with said body portion, whereby the work may be accurately positioned on the block for manipulation, and in the opposite direction to reseat, said head piece on said body portion upon the positioning of the work, and means for operating upon the work to shape the same relatively to the coöperating parts of said block.

6. A hat block comprising a body portion having an upwardly directed flange surrounding the upper edge thereof, a detachable head piece adapted to rest upon and mate with said body portion to form a complete block, said head piece being shaped to lie within said flange to provide a recess between said flange and said head piece, and a former adapted to register with said recess.

7. A hat block comprising a body portion having an upwardly directed flange formed by an extension of the side wall thereof, a detachable head piece adapted to mate with said body portion to produce a complete block, said head piece being shaped to lie within said flange and provide a recess between said flange and said head piece, means carried by said head piece and adapted to movably engage with said body portion, whereby said head piece may be adjusted in a vertical plane relatively to said body portion, means for locking said head piece

in adjusted position, means for locking said head piece in engagement with said body portion and a former adapted to coöperate with said block, for the purposes described.

8. A hat block comprising a body portion, the wall thereof being extended upwardly to provide a flange surrounding the top of said body portion, a solid head piece shaped to normally lie within said flange and of a size to provide a recess formed by said flange and the wall of said head piece, means carried by said head piece for raising the same out of engagement with said body portion for the application of work to the block for manipulation, means for securing the work to the body portion of said block, means for reseating and locking said head piece in engagement with the body portion when the work has been applied to said block and means arranged for operating upon the work in coöperation with said body portion and said head piece, for the purposes described.

9. A telescoping device for hats comprising a block consisting of a body portion and a detachable head portion, said head portion being provided with means rigidly secured thereto and movable within said body portion to render said head piece vertically adjustable relatively to said body portion, and means for locking said head piece in such adjusted position.

10. A telescoping device for hats comprising a block, consisting of a body portion and a vertically adjustable solid head piece mounted on said body portion, means being provided on said body portion to coöperate with said head piece to provide a die, and a former adapted to coöperate with said die to shape the work.

11. A two-piece hat block having a body portion and a head piece, means connected to said head piece and coöperating with said body portion, whereby said head piece may be vertically adjusted relatively to said body portion for positioning the work, and means for seating said head piece on said body portion when the work has been positioned, and means adapted to coöperate with said body portion and said head piece to conform the work.

In witness whereof I have hereunto set my hand in the presence of two subscribing witnesses.
